UNITED STATES PATENT OFFICE.

ROBERT L. ATWELL, OF BELOIT, WISCONSIN.

TRAFFIC-SIGNAL FOR VEHICLES.

1,351,605.

Specification of Letters Patent. Patented Aug. 31, 1920.

Application filed May 24, 1919. Serial No. 299,419.

To all whom it may concern:

Be it known that I, ROBERT L. ATWELL, a citizen of the United States, residing at Beloit, in the county of Rock and State of Wisconsin, have invented new and useful Improvements in Traffic-Signals for Vehicles, of which the following is a specification.

This invention relates to traffic signals and especially signals which are adapted to be mounted upon an automobile, motor truck or other motor propelled vehicle and by means of which the operators of other cars as well as traffic policemen and pedestrians may be advised as to any change in the direction of the vehicle contemplated by the operator thereof without the necessity of the operator extending his arm for that purpose thereby enabling him to use both arms and hands in the control of the machine.

The invention contemplates the use of a pointer or indicator for the direction in which the car is to be operated, which pointer is illuminated so that it may be used after night-fall as well as during the daytime, combined with means for swinging said arm in vertical plane either in line with the path of travel of the machine or in a plane transverse to the direction of movement of the machine, thereby enabling the arrow to indicate exactly the direction to be followed by the machine.

A further object in view is to provide a traffic signal the several parts of which may be readily applied to any machine either at the time of manufacture thereof or at any time subsequent thereto.

With the above and other objects in view, the invention consists in the novel construction, combination and arrangement of parts herein fully described, illustrated and claimed.

In the accompanying drawings:

Figure 1 is a perspective view of the improved traffic signal shown in its applied relation to a motor vehicle.

Fig. 2 is an enlarged longitudinal section through the indicator or traffic signal operating means.

Fig. 3 is a plan view of the cam rod.

Fig. 4 is a fragmentary elevation of the rack and pinion transmission mechanism.

Fig. 5 is a section on the line 5-5 of Fig. 2.

Fig. 6 is a section on the line 6-6 of Fig. 2.

Fig. 7 is a rear elevation showing the vertical position of the pointer in full lines and the right and left hand positions thereof in dotted lines.

Fig. 8 is a face view of the pointer or indicator.

Fig. 9 is a longitudinal section through the same.

Fig. 10 is a plan view of the operating lever mounted on the head of the steering car.

Fig. 11 is a plan view of the graduated sector.

The traffic signal comprises a signaling arm or pointer 1 which is shown in the form of an arrow of hollow formation, comprising rear and front walls 2 and 3 and side walls 4, the face wall of the pointer being composed of glass or other translucent material so as to be visible after night-fall when interiorly illuminated by means of electric lamps or bulbs 5 which are disposed at intervals throughout the length of the burner and within the base or hub portion thereof as shown in the drawing, the wires leading to said lamps or bulbs passing through an opening 6 in the body of the arm or pointer as shown.

The pointer or arm 1 is mounted upon an oscillatory or partially rotatable support or hub 7 having a journal 8 which is mounted rotatably in a bearing 9 carried by an arm 10 supported in a manner hereinafter particularly described, the hub or support 7 being mounted between the arm 10 and another arm 11, the latter being employed for imparting a partial rotary or rocking movement to the support 7 as will hereinafter appear.

The arm 11 is connected integrally to or suitably fastened in fixed relation to a rotatable cam rod 12 which is journaled in a main supporting bearing 13, having an attaching base 14 by means of which it is fixedly secured to the vehicle. The cam rod 12 has a cam groove 14 extending longitudinally thereof and comprising a straight longitudinal portion 15 and inclined portion 16 leading off therefrom, and a reversely inclined portion 17 of greater extent than the inclined portion 16. The cam groove 14 is engaged by a pin 18 having a fixed connection with the stationary bearing 13, where-

2

by as said cam rod is shifted longitudinally through the bearing 13, a partial rotative movement is imparted thereto first in one direction and then in the opposite direction.

5 The longitudinal portion 15 of the cam groove permits the cam rod to be shifted longitudinally to a certain extent or degree without any turning movement of said cam rod.

10 The arm 10 is provided at its inner end with a sleeve 18^a having one or more grooves 19 to receive a corresponding number of keys or ribs 20 on the arm 11 where it passes through said sleeve 18^a. The sleeve 18^a is 15 provided with annular grooves 21 having spiral portions 22 which open out at the inner end of the sleeve and working in the grooves 21 are the inturned end portions 22 of a pair of yokes or studs 23 which are 20 adjustably secured by means of nuts 24 and 25 to oppositely extending lugs 26 on the fixed or stationary bearings 31. The members 23 thus serve to prevent any movement of the sleeve 18^a longitudinally with respect 25 to the axis of the bearing member 13 while the longitudinal portion 15 of the cam groove is moving along the pin 18. When however, the pin 18 enters and moves along the inclined portions of the cam groove, the 30 sleeve 18^a is partially rotated until the members 23 pass out of engagement therewith and release the sleeve 18^a.

The cam rod 12 is formed with a bore 27 which receives an operating push rod 28 35 adjustable in the bore 27 to provide for properly adjusting the traffic operating mechanism in relation to the motor vehicle upon which it is mounted. The push rod 28 may be connected by any suitable means 40 such as a lever or link to an operating shaft 29 extending upwardly through the steering column 30 of the machine and having secured to its upper end an operating lever 31 designed to sweep over an arcuate graduated plate or sector 32 having suitable emblems thereon to designate such direction as left, right, turn and stop as may be found desirable by the manufacturer. It will now be understood that by operating the lever 35 31, the push rod 28 is moved longitudinally thereby imparting a corresponding movement to the cam rod 12, causing the latter to slide through the bearing 13 and causing the cam groove of said rod to engage the fixed pin 18, thus imparting a partial rotary movement to the cam rod during the longitudinal movement thereof.

Normally the signal arm or pointer 1 lies in a horizontal plane pointing in a straight 60 forward direction or in a direction of travel of the machine. In the initial rearward movement of the cam rod, the straight portion 15 of the cam groove engages the pin 18 so that said cam rod is not rotated but 65 moved rearwardly, carrying with it the arm

11. Said arm 11 is provided with a rack face 33 which engages a gear face 34 on a short stub shaft or journal 35 extending from the adjacent edge of the support or hub 7 above described. As a result a partial 70 rotative movement is imparted to the support 7, causing the pointer or indicating arm to travel through an arc of ninety degrees or from a straight forward horizontal position to an upright position, said arm or 75 indicator moving in a vertical plane in line with the direction of movement of the vehicle. In the further rearward movement of the cam rod 12 the pin 18 engages the inclined portion 16 of the cam slot or groove 80 thereby imparting a partial rotative movement to the arm 11 and turning the indicator or pointer to an arc of ninety degrees so that it occupies a horizontal position and points laterally to one side of the machine. 85 In the further rearward movement of the cam rod 12, the pin 18 engages the longer and reversely inclined portion 17 of the cam groove and thereby turns the signaling arm or pointer to an arc of 180 degrees so that 90 said arm occupies horizontal position pointing directly toward the opposite side of the machine. By returning the lever 31 to its initial position, the movements hereinabove described are reversed and the indicating 95 arm or pointer is returned to its normal position in which it points straight forward and lies in a horizontal plane!

In Fig. 1 of the drawing, I have illustrated the indicator arm or pointer as 100 mounted and arranged to operate at the rear of the motor vehicle but it will of course be apparent that said signaling arm or pointer may be arranged at the front of the vehicle or in any other desired position, the main feature of the invention residing in the means for swinging said indicating arm or pointer in a plurality of vertical planes so that it may be disposed in several positions to indicate clearly and unmistakably the direction in which the vehicle is about to travel. This is a great assistance to the drivers of other vehicles especially those traveling in rear of the vehicle equipped with the signaling apparatus and the mechanism is also useful to traffic policemen and pedestrians as they serve to advise the traffic in general as to the intended movement of the vehicle. The motion transmitting means between the initial operating lever 21 and the push rod 28 may be varied in accordance with the type of vehicle in conjunction with which the traffic signal is to be used, for example electrical means may be employed and I therefore do not desire to be restricted to any particular form of operating connection for that purpose. It will also be apparent that the particular means for imparting a partial rotative movement to the support 7 may be varied without departing 115 120 125 130 135 140 145 150 155 160 165 170 175 180

from the principle of the invention as other means than the rack and pinion mechanism shown and described may be resorted to. The traffic signal eliminates the necessity of the operator using the arm to signal the direction in which he is about to turn thereby leaving his arms and hands free to manipulate the control of the machine. The mechanism is not only simple but is strong and reliable involving no delicate parts liable to get out of order and therefore it is able to stand the strains of rough usage, especially adapted to all types of commercial cars whether used for pleasure or industrial use.

What I claim is:—

1. In a vehicle carried traffic signal, a signal supporting member, a direction indicating and pointing member having an articulated connection with said supporting member adapting it to be swung in a vertical plane in line with the direction of movement of the vehicle and also in a vertical plane at substantially a right angle to the direction of movement of the vehicle, and means for swinging said direction indicating member in either of said vertical planes, the last named means comprising a rockable element by which said indicating member is carried, including a push rod geared to said rockable element, and means including a cam device for rocking said element on an axis substantially at a right angle to its major axis, and a manually operable element controlling both of the last named means.

2. In a vehicle carried traffic signal, a signal supporting member, a direction indicating and pointing member having an articulated connection with said supporting member adapting it to be swung in a vertical plane in line with the direction of movement of the vehicle and also in a vertical plane at substantially a right angle to the direction of movement of the vehicle, and means for swinging said direction indicating member in either of said vertical planes, the last named means comprising a rockable element by which said indicating member is carried, means for rocking said element on the major axis, an arm supporting one end of said element and adapted to

turn the same end for end, and another arm adapted to turn said element on its major axis.

3. In a vehicle carried traffic signal, a signal supporting member, a direction indicating and pointing member having an articulated connection with said supporting member adapting it to be swung in a vertical plane in line with the direction of movement of the vehicle and also in a vertical plane at substantially a right angle to the direction of movement of the vehicle, and means for swinging said direction indicating member in either of said vertical planes, the last named means comprising a rockable element by which said indicating member is carried, means for rocking said element on the major axis, an arm supporting one end of said element and adapted to turn the same end for end, and another arm adapted to turn said element on its major axis, and a single manually operable element controlling both of said arms.

4. A signal device for vehicles comprising a support adapted to be secured upon a vehicle, a member slidable and rotatable through said support, an arm carried by said member and having rack teeth thereon, a bracket arm having slidable connection with said member, a pointer having a hub portion journaled in the free end of said bracket arm, and a pinion extending from said hub and meshing with said rack.

5. A vehicle carried signal comprising a support adapted to be secured upon a vehicle and having a bore, a rod slidable and rotatable within said bore and having a cam groove, a pin within the bore engaging with the groove, an arm secured to and projecting from one end of said rod and formed with rack teeth, a bracket arm having one end formed to slidably receive said arm and having spiral grooves, yokes projecting from said support and having angular ends engaging within said spiral grooves, a pointer having a hub member journaled at one end in the free end of said bracket arm, and a pinion at the other end of said hub portion meshing with said rack teeth.

In testimony whereof I affix my signature.

ROBERT L. ATWELL.
